PREPARATION OF SILICON TETRAFLUORIDE

Franciszek Olszewski, Freeport, Tex., assignor to The Dow Chemical Company, Midland, Mich., a corporation of Delaware

Filed Sept. 2, 1958, Ser. No. 758,436

9 Claims. (Cl. 204—61)

This invention relates to a process for preparation of silicon tetrafluoride, and more particularly, to the preparation of this compound by the electrolysis of a non-volatile molten metal fluoride containing a metal silicate or silica.

This application is a continuation-in-part of patent application Serial No. 663,966, filed on June 6, 1957, now abandoned.

Metal fluorides, metal silicates and silica are cheap raw materials and a process whereby silica tetrafluoride can be prepared by the electrolysis of these fused metal salts considerably reduces the production cost of this compound.

It is, therefore, among the objects of this invention to provide a process for the preparation of silicon tetrafluoride by electrolysis of a fused metal fluoride containing a metal silicate or silica.

The above and other objects are attained by passing an electric current through a molten electrolyte between a porous carbon anode and an insoluble cathode where the electrolyte consists essentially of a mixture of a metal fluoride which is non-volatile and stable at the electrolysis temperature selected from the group consisting of alkali metal fluorides, alkaline earth metal fluorides, earth metal fluorides, and mixtures thereof and a metal silicate which is non-volatile and stable at the electrolysis temperature or silicon dioxide.

It has been discovered that when a porous carbon anode is used in the electrolysis of an electrolyte consisting essentially of the particular metal fluoride or fluorides and a metal silicate or silica, an anode product is obtained containing silicon tetrafluoride. The anode product will contain a number of fluorine-containing compounds including both saturated and unsaturated fluorocarbons as well as the silicon tetrafluoride. The anode product may be gaseous at the electrolysis temperature, but may contain higher molecular weight fluorocarbons which are oils at room temperature. With a porous carbon anode, the fluorine-containing compounds are obtained by the electrolysis without encountering "anode affect."

The porous carbon anode used may be an intimately combined solid mass type which is made by combining amorphous carbon, such as petroleum coke, coal, carbon black etc. or allotropic carbon, such as graphite, with a binder and sintering the mixture to form an intimately combined solid mass having a prescribed permeability. Also, the porous anode may consist of carbonaceous material in particulate form confined so that the individual particles are in electrical contact with each other. A porous carbon anode which is intimately combined by sintering to form a solid porous cohered mass is generally preferred.

A solid mass type porous anode having a permeability of at least one and not greater than 40 is generally used. It is preferred that the permeability be in the range of 4 to 20. While an anode having a permeability less than

2

one may be used in special cases, no beneficial advantage is obtained. The maximum anode current density which may be used without encountering anode effect is proportional to the permeability, increasing with an increase in permeability. With the permeabilities generally used, in the range of 1 to 40, normally all practical anode current densities may be used without encountering this objectionable phenomenon. In special cases, however, where relatively low current densities are to be employed an anode having a permeability as low as 0.2 may be used, if desired. An anode having a permeability greater than 40 is seldom used. The structural strength of the anode decreases with the porosity which makes it less desirable than a less porous anode.

15 "Permeability" as used herein, refers to the porous anodes which are intimately combined in a solid mass by sintering and is expressed as the amount of air passing through the porous carbon anode in cubic feet per minute per square foot per inch thickness at a pressure differential of 2 inches of water. The term "porous," as used herein, means gas permeable.

While the current efficiency and the yield of silicon tetrafluoride may not be as great, a porous anode comprising of carbonaceous material in particulate form

25 loosely confined is less costly and thus may be desirable in some cases. Practically any carbonaceous material in particulate form may be used. Charcoal, coke, lamp black, powdered carbon, and powdered graphite are illustrative examples of some of the carbonaceous materials

30 which are operative. Due to its availability petroleum coke in particulate form is preferred. Generally particles of the carbonaceous material larger than one inch are not used except in a large unit where a large bed is employed. Particles as small as those passing through a No. 200 standard mesh screen and being retained on a No. 300 mesh screen are operative. However, it is preferred to use carbonaceous material which will pass through a No. 6 standard mesh screen and be retained on a No. 40.

40 The invention may be more easily understood when the detailed discussion is considered in conjunction with the drawings, in which:

Figure 1 diagrammatically illustrates an electrolytic cell employing a porous anode comprising of carbonaceous material in particulate form loosely confined which may be used in carrying out the invention, and

Figures 2 and 3 show different types of porous anode assemblies which may be used in the cell shown in Figure 1 when a solid mass type porous anode is used.

The electrolytic cell diagrammatically shown in Figure 1 comprises a metal tank 1 having a cover plate 2 and an electrical non-conducting cylindrical liner 3 in which the electrolyte 4 is placed, and a carbon lead 5 extending part way into the tank through an opening in cover plate

55 2. As shown, cover plate 2 is fastened to tank 1 by means of a multiplicity of screws 6 to form a gas tight seal. Clamps or other means may be used. A pipe 7 is inserted in an opening 8 in cover plate 2 and provides a passage-way through which the anode gas produced as a product inside of tank 1 may be withdrawn from the tank. The attachment of pipe 7 to cover plate 2 is gas tight and may be obtained by welding the outer periphery of the pipe to the cover plate or by having the end which is inserted in the cover plate threaded and the opening 8 also threaded to receive the pipe. Where the carbon lead 5 passes through cover plate 2, an electrical insulating seal 9 is used so that the gas tight seal is obtained. An electrical lead 10 through which the current is supplied to the cell is attached to the carbon lead at the end which is not inserted into the tank. Another lead 11 is electrically connected to the surface of the tank which through a mol-

60 65 70

ten cathode 12 at the bottom of the tank completes the circuit for the current flow through the electrolytic cell. A molten cathode of an inert metal, such as lead, heavier than the electrolyte is generally used where the metal to be deposited is lighter than the electrolyte. This simplifies the construction of the cell, since no provisions have to be made to entrap or remove the metal deposited from the surface of the electrolyte. Carbonaceous material 13 in particulate form which being lighter than the molten electrolyte floats on the surface surrounding and in contact with carbon lead 5. Carbon lead 5 is not immersed in the electrolyte itself.

In the operation of the cell, the cell is heated to the desired temperature. When the desired temperature is obtained an electrical potential is applied to leads 10 and 11 to provide a current flow through the electrolyte. The anode product which may be substantially all gaseous is withdrawn from within the tank through pipe 7. It is then further processed by known methods to recover and separate the particular fluorocarbons obtained. The metal depositing out from the electrolyte is deposited in the molten cathode and later recovered by known methods.

Figures 2 and 3 illustrate a porous anode assembly wherein a solid mass type of a porous anode is used. As shown in Figure 2 the anode assembly comprises a cylindrical carbon or graphite anode holder 20 having a passageway 21 extending through the center along its longitudinal axis. A hollow-cup shaped piece of porous carbon 22 is attached to the lower end of holder 20 with passageway 21 communicating with a hollow inside area 23 of the porous cup 22. At the upper end of holder 20, a pipe 24 is inserted in passageway 21 and thus provides a means by which the anode product forming at the porous cup may be removed from the cell. A lead 25 is attached to holder 21 and thus supplies the current to the anode and provides a means for completing the circuit in the cell.

Figure 3 shows a modification of the porous anode assembly shown in Figure 2. It comprises a carbon or graphite carbon holder 30 which at its lower end 31 is enlarged. The holder has a passageway 32 extending along its longitudinal axis which becomes enlarged at the lower end. The porous anode 33 in the shape of a plug is inserted in the lower end of the anode holder 30 in the enlarged area of the passageway. A pipe 34 is inserted in passageway 32 at the upper end of the anode holder. In the operation of the cell the porous anode portion of the anode assembly as shown in Figures 2 and 3 are immersed in the electrolyte.

The shape of the porous carbon anode used is immaterial. The hollow-cup type as shown in Figure 2 or the plug type as shown in Figure 3 are preferred especially where higher molecular weight fluorocarbons may be obtained. These fluorocarbons may be readily drawn through the porous anode and removed from the system through the passageway in the holder. Instead of using a hollow-cup type porous anode as shown in Figure 2 or a plug as shown in Figure 3, a solid cylindrical piece of the porous carbon material may be used as an anode. It may be necessary in some cases to use a hood or shield to enclose the solid anode to entrap the anode gases as they are formed and released in order to remove them from the system. Other types of anode assemblies which are apparent to those skilled in the art may also be used.

Illustrative examples of the alkali metal, alkaline earth metal and earth metal fluorides which may be used as the fluoride constituent of the electrolyte are magnesium fluoride, aluminum fluoride, sodium fluoride, barium fluoride, strontium fluoride, calcium fluoride, lithium fluoride, and cesium fluoride. These metal fluorides are non-volatile and stable at electrolysis temperature. Generally in the electrolysis the same fluorine-containing compounds are obtained regardless of the particular metal fluoride used as the fluoride constituent of the electrolyte. How-

ever, the ratio of the silicon tetrafluoride obtained in the anode product may vary somewhat with the metal fluoride employed.

Although only one of the alkali metal fluorides, alkaline earth metal fluorides, or earth metal fluorides may be used as the fluoride constituent of the electrolyte, a mixture of these metal fluorides is often used to increase the conductivity or lower the melting point of the bath. For this purpose, lithium fluoride is most commonly added to the other metal fluorides, but other mixtures and combinations may also be used. When other fluorides are added to either increase conductivity or lower the melting point of a particular metal fluoride bath, the fluorides of metals which are higher in the electromotive series or more electronegative than the metal to be extracted at the cathode from the particular bath are preferred. By using fluorides of metals more electronegative, these metals will not deposit out at the cathode with the desired metal except at exceptionally high cathode current densities. Thus, the cathode product is not contaminated under normal operation conditions. Also in continuous operation of the cell, the metal fluoride added to the electrolyte is not depleted by the electrolysis and only the fluoride of the particular metal being deposited at the cathode has to be added continuously. For example, when lithium fluoride is added to a magnesium fluoride bath, the lithium is more electronegative than magnesium and thus will not deposit out at the cathode. Once the lithium fluoride is added to the bath it will not be depleted by the electrolysis and only magnesium fluoride has to be added for continuous operation.

Illustrative examples of the metal fluoride mixtures that may be used and the metal preferentially deposited out at the cathode are shown in the table below.

Fluoride mixture:	Metal preferentially deposited at the cathode
NaF·LiF	Na
MgF ₂ ·LiF	Mg
BaF ₂ ·LiF	Li
AlF ₃ ·LiF	Al
AlF ₃ ·NaF	Al
AlF ₃ ·NaF·LiF	Al
AlF ₃ ·CaF ₂ ·MgF ₂	Al
MgF ₂ ·LiF·NaF	Na
MgF ₂ ·LiF·CaF ₂	Mg
MgF ₂ ·NaF	Na
MgF ₂ ·CaF ₂	Mg
AlF ₃ ·LiF·MgF ₂	Al
YF ₃ ·LiF	Y

To the metal fluoride or mixture of fluorides, silica or a metal silicate which is non-volatile and stable at the electrolysis temperature is added. By the electrolysis of the resulting electrolyte consisting essentially of the metal fluoride or metal fluorides and the silicon containing compound, silicon tetrafluoride is obtained. When a metal silicate is used as a constituent in the electrolyte, it is preferred to add the silicate of the same metal as that of the fluoride constituent of the electrolyte which is being deposited at the cathode in the bath. Thus, the cell can be continuously operated by just adding the metal fluoride electrolyte and the particular silicate. A non-volatile and stable silicate of the same metals as the alkali metals, alkaline earth metals, or earth metals of the fluoride which may be used other than the particular metal utilized in the bath may also be used. However, the metal of the silicate may continuously increase in the cell, if it is higher in the electromotive series, or deposit out at the cathode with the desired metal of the bath, if lower. In special cases, non-volatile and stable silicates of metals other than those of the fluorides which may be used in the electrolyte may also be used. Most of these other metals are lower on the series and will de-

posit out at the cathode in conjunction with the electrolyte metal. Illustrative examples of these other metal silicates are manganese metasilicate and lead metasilicate.

The energy required for the production of the fluorine-containing compound is generally higher than for the production of compounds containing other anions. Consequently, a higher concentration of the fluoride in the bath is generally maintained to obtain a greater formation of the fluorine-containing compounds. Generally, a mole ratio of the fluoride to the silicate or silica in the range of 10:1 to 80:1 is used, preferably in the range of 20:1 to 40:1.

While an anode product containing a higher percentage of silicon tetrafluoride is normally obtained at lower temperatures, an electrolysis temperature in the range of 700° to 1000° C. is generally used. The optimum of the temperature for a particular electrolyte may vary somewhat. The minimum temperature that may be employed is the melting point of the electrolyte used, since the electrolyte must be in the molten state. The maximum temperature is either limited by cell structure, the stability and volatility of the particular electrolyte employed or metal silicate added to the bath, or the thermal stability of the particular fluorine compound desired at the anode. Since at a lower temperature the construction of the cell is simplified, a temperature in the range of 700° to 1000° C. is thus generally preferred within which range an anode product containing a relatively high percentage of silicon tetrafluoride is obtained. However for an electrolyte containing a LiF-NaF-AlF₃ mixture as the fluoride constitute, the optimum temperature is somewhat lower being in the range of 650° to 800° C.

Although anode current density below 1 and up to 100 amperes per square inch may be used with certain porous anodes, an anode density in the range of 1 to 40 amperes is generally employed, preferably in the range of 1 to 10 amperes per square inch. Generally, at a higher anode current density, the anode product contains a higher percentage of silicon tetrafluoride. With an anode of carbonaceous material in particulate form loosely confined, an anode current density of over 5 amperes per square inch is seldom used due to the high voltage required. The cathode current density is generally in the range of 1 to 30 amperes per square inch. To obtain the current densities desired a voltage up to 30 volts may be employed, but a voltage in the range of 4 to 10 is preferred. For the loosely confined anode, a higher voltage may be required to obtain the desired anode current density.

Various electrolytic cell construction and various types of anodes which are apparent to those skilled in the art may be used. The particular anode adopted will generally depend upon the metal being deposited in the cell.

The term "earth metals," as used herein, means the elements aluminum, scandium, yttrium and lanthanum of the third group of the periodic system.

The term "stable," as used herein in reference to the metal fluoride and metal silicates, means salts which are thermally stable and will not decompose due to temperature itself.

The term "non-volatile" as used herein in reference to the metal fluoride and metal silicates, means salts which do not have a vapor pressure in excess of 20 mm. of Hg at the electrolysis temperature.

The following example further illustrates the invention but is not to be construed as limiting it thereto.

Example I

An electrolytic cell was employed in the preparation of silicon tetrafluoride. The cell comprised a steel crucible with an alumina liner and was similar to that shown in Figure 1 except that a porous anode assembly similar to that shown in Figure 3 was used instead of the particulated carbonaceous material. The porous anode plug

was approximately 1½ inches in diameter and 1½ inches long.

To the cell, approximately 1200 grams of an electrolyte comprising 52 weight percent sodium fluoride and 48 weight percent of lithium fluoride were added. The electrolyte was heated to 725° C. and 600 grams of lead added to serve as the cathode. The cell was operated for approximately one hour at current of 20 amperes and 9 volts. Then 16 grams of calcium silicate were added and stirred into the bath. The cell was operated for an additional hour at a current of around 20 amperes and the anode gas was collected during this period.

The analysis of the anode gases indicated the following analysis in mole percent:

	Component:	Percent
15	SiF ₄	4.4
	CF ₄	30.0
	C ₂ F ₆	30.0
20	C ₃ F ₈	6.9
	CO ₂	9.5
	CO	9.5

In a manner similar to above, SiO₂, Li₂SiO₃, MgSiO₃, and other non-volatile and stable silicates may be substituted for the calcium silicate to obtain similar anode products. Also other fluoride electrolytes such as MgF₂-LiF, MgF₂-NaF-CaF₂ may be employed in place of the NaF-LiF electrolyte used above.

Example II

In a cell similar to that described in Example I approximately 1000 grams of a mixture containing 48 weight percent lithium fluoride and 52 weight percent sodium fluoride were added to the cell. Approximately 410 grams of lead were added to the cell to act as a molten cathode. After the cell was heated to a temperature of 650° C., 50 grams of sodium metasilicate (Na₂SiO₃) were added. An anode assembly, similar to that of Example I except that the porous anode plug was 1 inch in diameter and 1 inch long, was immersed in the electrolyte. A current of 20 amperes at a potential of 24 volts was passed through the electrolyte for 1½ hours while the electrolyte temperature was maintained in the range of 650° to 710° C. The anode product obtained was analyzed by infra-red. The anode product contained the following in mole percent on an air-free basis.

CO ₂	20.2
CF ₄	38.0
C ₂ F ₆	24.0
SiF ₄	9.9

What is claimed is:

1. A process for the preparation of silicon tetrafluoride which comprises passing an electric current through an electrolyte between a porous carbon anode and an insoluble cathode at a temperature sufficient to melt the electrolyte to obtain an anode product containing silicon tetrafluoride, said electrolyte consisting essentially of a mixture containing at least one metal fluoride which is non-volatile and stable at the electrolysis temperature selected from the group consisting of alkali metal fluorides, alkaline earth metal fluorides, and earth metal fluorides and a compound selected from the group consisting of metal silicates which are non-volatile and stable at the electrolysis temperature and silica, and recovering the silicon tetrafluoride from the anode product.

2. A process for the preparation of a silicon tetrafluoride which comprises passing an electric current through an electrolyte between a porous carbon anode and an insoluble cathode at a temperature sufficient to melt the electrolyte to obtain an anode product containing silicon tetrafluoride, said electrolyte consisting essentially of a mixture containing at least one metal fluoride which is non-volatile and stable at the electrolysis temperature selected from the group consisting of alkali

metal fluorides, alkaline earth metal fluorides, and earth metal fluorides and a compound selected from the group consisting of metal silicates which are non-volatile and stable at the electrolysis temperature and silica in an amount such that the mole ratio of the fluoride to the compound in the electrolyte is in the range of 10:1 to 80:1, and recovering the silicon tetrafluoride.

3. A process according to claim 2 wherein the electrolyte consists essentially of at least one alkali metal fluoride which is non-volatile and stable at electrolysis temperature and a metal silicate which is non-volatile and stable at electrolysis temperature.

4. A process according to claim 2 wherein the electrolyte consists essentially of at least one alkaline earth metal fluoride which is non-volatile and stable at electrolysis temperature and a metal silicate which is non-volatile and stable at electrolysis temperature.

5. A process according to claim 2 wherein the electrolyte consists essentially of at least one earth metal fluoride which is non-volatile and stable at electrolysis temperature and a metal silicate which is non-volatile and stable at electrolysis temperature.

6. A process according to claim 2 wherein the electrolyte consists essentially of a mixture of an alkali metal fluoride and an alkaline earth metal fluoride and a metal silicate which are non-volatile and stable at electrolysis temperature.

7. A process for the preparation of silicon tetrafluoride which comprises passing an electric current through an

5
electrolyte between a porous carbon anode and an insoluble cathode at a temperature sufficient to melt the electrolyte to obtain a product at the anode containing silicon tetrafluoride, said electrolyte consisting essentially of sodium fluoride, lithium fluoride, and a metal silicate which is non-volatile and stable at the electrolysis temperature in an amount such that the mole ratio of the fluoride to the silicate in the electrolyte is in the range of 20:1 to 40:1.

10
8. A process according to claim 7 wherein the metal silicate is calcium silicate, the porous carbon anode is an intimately combined solid mass having a permeability in the range of 4 to 20, and the electrolyte is at a temperature in the range of 700° to 1000° C.

15
9. A process according to claim 7 wherein the metal silicate is sodium silicate, the porous carbon anode is an intimately combined solid mass having a permeability of at least 0.2, and the electrolyte is at a temperature in the range of 700° to 1000° C.
